D8/383Primary Examiner—Theodore M. Shooman
Assistant Examiner—Paula Mortimer[57] **CLAIM**

The ornamental design for a comfort clip for a seatbelt, as shown and described.

DESCRIPTION

FIG. 1 is a front elevational view of a comfort clip for a seatbelt showing my new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The broken line showing of the seatbelt in FIG. 4 is for illustrative purposes only and forms no part of the claimed design.
